CLAIM

The ornamental design for a portion of a wall of an escalator, moving walkway, elevator, or lifting apparatus, as shown and described.

DESCRIPTION

The drawing FIGURE is a front view of a portion of a wall of an escalator, moving walkway, elevator, or lifting apparatus. The broken lines surrounding the portion of a wall of an escalator, moving walkway, elevator, or lifting apparatus represent unclaimed environmental structure and the boundaries of the clam and form no part thereof.

The portion of a wall of an escalator, moving walkway, elevator, or lifting apparatus is flat and planar.
